UNITED STATES PATENT OFFICE.

JOHN WICKS, OF CHICAGO, ILLINOIS, ASSIGNOR TO AUTOMATIC ELECTRIC COMPANY,
OF CHICAGO, ILLINOIS, A CORPORATION OF ILLINOIS.

TELEPHONE SYSTEM.

1,315,444.

Specification of Letters Patent.

Patented Sept. 9, 1919.

Application filed October 7, 1916. Serial No. 124,358.

To all whom it may concern:

Be it known that I, JOHN WICKS, a citizen of the United States of America, and a resident of Chicago, county of Cook, and State 5 of Illinois, have invented certain new and useful Improvements in Telephone Systems, of which the following is a specification.

My invention relates in general to telephone systems but is concerned more particularly with methods of handling toll or long distance connections in automatic telephone systems. The object of the invention may be said to consist broadly in the production of a new and improved toll trunking 15 system in which long distance connections are established automatically, together with the design of improved circuits and apparatus whereby such systems may be put into effective operation.

20 The above indicates in broad terms the scope of the invention. Various features are included in the working embodiment of the complete system which will not now be specifically mentioned, but which will each be described in the specification which is to 25 follow and pointed out in the claims.

Of the accompanying drawings, to which reference will be made in the specification, Figures 1, 2, 3, 4, 5, 6, 7, 8, 9, 10, and 11, 30 when arranged in order with corresponding lines at the ends thereof in alinement, represent diagrammatically a complete long distance connection between a calling substation A in one exchange and a called substation A³ in another exchange, in a system embodying the principles of my invention. Fig. 12 is a schematic diagram illustrating 35 the general layout of the system, and Fig. 13 is a detail of the bank of the automatic switch shown in Fig. 6.

40 Referring to Fig. 12, three automatic exchanges are shown which, beginning at the left, will be designated, respectively, as the No. 1 exchange, the No. 2 exchange, and the No. 3 exchange. These exchanges are assumed to be located in different cities and may each be of 10,000 lines capacity although the exact size is of no great consequence. On the assumption that the capacity is as noted 45 above however, local connections in each exchange will be established through the medium of individual line switches or trunk selectors, first selectors, second selectors, and connectors. For example, in the No. 1 exchange, the subscriber at substation A is

able to establish connection with the subscriber at substation A' through the medium of the individual line switch C, the first selector switch E, the second selector switch F, and the connector switch H'. This is the 60 usual percentage trunking system and is thus briefly mentioned because of the fact that a portion thereof comprising the connector switches also forms a part of a second trunking system used only for the establishment 65 of toll connections.

Each exchange is provided with a toll board presided over by operators who establish all outgoing toll connections. The operators in any particular exchange have access 70 to the local subscribers' lines over so called toll service trunks, each of which terminates in a toll first selector. The toll first selectors have access to toll second selectors, which in turn have access to connector switches. 75 These latter switches are the connectors previously mentioned as forming part of the local trunking system. Referring to the drawing Fig. 12 again, the jack J is the terminal of a toll service trunk which extends 80 to the toll first selector V'. The toll selector V' has access to toll second selectors, one of which is the toll selector W', which in turn has access to connector switches, one of which is the connector H'. It will be 85 seen therefore that the local trunking system and the toll service trunking system are finally blended together, in that the connector switches are common to both systems. The No. 2 and the No. 3 exchanges are both 90 arranged in substantially the same manner as is exchange No. 1.

Proceeding now to the trunking between exchanges, the No. 1 exchange and the No. 2 exchange may be interconnected by a 95 group of toll lines sufficient in number to handle the traffic. One of these toll lines is the toll line X. Similarly, another group of toll lines, one of which is the toll line Z, connects the No. 2 exchange with the No. 3 100 exchange. There are no toll lines directly extending between the No. 1 and the No. 3 exchanges, therefore connections between these two points must necessarily be established via the No. 2 exchange. This situation 105 may arise in two ways: Either or both of the No. 1 and No. 3 exchanges may be of relatively small size and so located as to be subsidiary to exchange No. 2. In such case it would usually be uneconomical to provide a third 110

group of toll lines extending directly between the No. 1 and No. 3 exchanges. The second case arises when the exchanges, which may all be of large size, are located in approximately a straight line or where for topographical reasons the toll lines from exchange No. 1 to exchange No. 3 pass through or near the city in which exchange No. 2 is located. Under these circumstances, and assuming that toll connections are to be established automatically, it has been found most efficient to cut the through toll lines at the intermediate exchange, thereby making each section available for short haul messages, and complete all the through calls by means of switching apparatus at the intermediate or No. 2 exchange.

It will be perceived now that the toll lines and switching apparatus comprise a third trunking system, and it will be shown in the following that this third system is merged into the toll service trunking system at each exchange. The toll lines terminate at each end in the usual manual drops and jacks. Thus the toll line X extends from jack J' in the No. 1 exchange to jack J² in the No. 2 exchange and the toll line Z extends from jack J⁴ in the No. 2 exchange to jack J⁵ in the No. 3 exchange. In addition there is provided for each toll line a toll selector repeater at each end thereof, which in the case of toll line X are the selector repeaters M and M', and in the case of toll line Z are the selector repeaters M² and M³. Considering now the No. 2 or intermediate exchange, the banks of all the toll selector repeaters, including repeaters M' and M², are connected in multiple and the first nine bank levels preferably (assuming that the usual Strowger type of switches are used) are multiplied with the first nine bank levels of the toll first selectors. Thus in Fig. 12 it will be seen that the toll second selector W² is accessible to toll first selector V² and to toll selector repeaters M' and M². The tenth bank level of the toll first selectors is dead because the tenth level of the local first selectors is used for calling recording toll operators and therefore does not correspond to a group of subscribers' lines. Since the toll operators are never required to call the recording operators there is thus left available for other purposes the tenth level of the toll first selectors and the same level of the toll selector repeaters. As previously mentioned no use is made of this level in the toll first selectors. In the toll selector repeaters, however, this tenth level is used for the through switching. To this end a group of toll rotary connectors is provided, one of which is indicated by reference character N. These toll rotary connectors are accessible in common to all the toll selector repeaters in the No. 2 exchange and have common access to all the groups of toll lines ter-

minating in the No. 2 exchange, it being understood, of course, that there may be a number of such groups, extending each to a different city, in addition to the two groups indicated in Fig. 12. No toll rotary connectors are shown in the No. 1 or No. 3 exchanges. In case there should be a fourth exchange beyond the No. 3 exchange, then the No. 3 exchange would take on the character of an intermediate exchange and would be equipped in the same manner as exchange No. 2.

To further elucidate the general trunking system, a call may be traced from the substation A in the No. 1 exchange to substation A² in the No. 2 exchange. The connection is, of course, handled by the operator in the No. 1 exchange and is extended to the called line over the following path: jack J', toll line X, toll selector repeater M', toll second selector W², and connector H². The connection to the local subscriber A is set up as follows: jack J, toll first selector V², toll second selector W², and connector H². Connection between jacks J and J' is completed by a cord circuit in the customary manner. Assuming now that the called substation is substation A² in the No. 3 exchange, the connection thereto may be extended over the following path: jack J', toll line X, toll selector repeater M', toll rotary connector N, toll line Z, toll selector repeater M³, toll second selector W³, and connector H³.

It is thought that the foregoing will be sufficient to make clear the general layout of the system. Reference will now be had to the circuit drawings, Figs. 1 to 11, inclusive, for a brief description of the apparatus involved. These drawings show diagrammatically all the equipment necessary to establish the complete long distance connection between substations A and A³, previously referred to. The apparatus shown in Figs. 1, 2, 3, and 4 is located in the No. 1 exchange; the apparatus shown in Figs. 5, 6, 7, and part of Fig. 8 is located in the No. 2 exchange; while the apparatus shown in the remainder of Fig. 8 and in Figs. 9, 10, and 11 is located in the No. 3 exchange.

The substations such as substation A (Fig. 1) and substation A³ (Fig. 11) may be of the usual common battery type in which the transmitter and receiver are connected in series. In addition, each substation is provided with an impulse sender or calling device which in the case of substation A includes the impulse springs 2 and 3 which are controlled by the impulse wheel 4 through the medium of a finger hole dial (not shown). A calling device suitable for the purpose is shown in British patent to S. G. S. Dicker, #29,654 of 1910.

The individual line switches such as line 130

switches C and C' may be of the general type of line switch described in the British patent to James, No. 26,301 of 1906; being, however, preferably of the particular type disclosed in U. S. Letters Patent No. 1,078,690, granted Jan. 17, 1912, to Frank Newforth. Line switches of the foregoing type are well known and therefore will not be described herein. It will be sufficient to

say that through the medium of line switch C the line of substation A is given access to a plurality of selector switches which form part of the local trunking system partially disclosed in Fig. 12. A three conductor trunk line which may be extended to one of these selector switches is indicated by reference characters 14, 15 and 16.

For the purpose of controlling a group of line switches such as the line switch C there is provided a master switch D, which is of the general type of master switch disclosed in British patent to James, #26,301 of 1906, above referred to; being, however, more nearly of the particular type disclosed in British patent to Martin, No. 1419 of 1910. The function of the master switch, as is well known, is to maintain all the idle line switches of its associated group in operative relation with an idle trunk line.

The selector switches, among which are included the toll selectors V', V², W', and W², the toll selector repeaters M, M', M², and M³, and also the local selectors E and F (shown only in Fig. 12) are mechanically of the general type of selector switch disclosed in U. S. Letters Patent No. 815,321, granted March 13, 1906, to Keith, Erickson and Erickson; the side switch and private magnet, however, being in all cases omitted, and the circuits being modified to enable the switches to operate in accordance with the two wire system of control.

The connector switches, among which are included the connectors H' and H² and the toll rotary connectors N and N' are mechanically of the general type of connector switch disclosed in U. S. Letters Patent #815,176, granted, March 13, 1906, to Keith, Erickson and Erickson. The connector switches, like the selectors, also have their circuits revised in accordance with two wire practice. Reference is had to U. S. Letters Patent #13,901, reissued April 13, 1915, to Frank Newforth, for circuits of a modern two wire automatic telephone system.

A great many other circuit changes have been made in order to enable the switches to operate in accordance with the general plan contemplated by my invention. For example, the connectors, such as connector H' (Fig. 1) serve to complete both local and toll connections. On connections of the former type the ringing is preferably automatic and the called subscriber is supplied with talking battery from the usual back

bridge relay of the connector. On toll connections, however, the ringing is operator controlled, while the called subscriber is supplied with talking battery from a bridge in the toll second selector. The busy test circuits operate differently also. Means is therefore provided in each connector which is effective to automatically switch its circuits whenever such connector is seized by a toll second selector.

Details of the toll second selector to which particular attention is called are the means for supplying talking battery to a called subscriber, mentioned above, and the means for relaying ringing current, which means comprises a normally bridged relay which is disconnected during conversation. The circuits of the toll rotary connector N (Fig. 6) are also new to a great extent, an important feature being the novel busy test circuits.

Attention is also particularly called to a feature of the toll selector repeaters, such as the selector repeater M' (Fig. 5). It will be observed that the line circuit through the selector repeater M (the heavy conductors) includes the repeating coil R'. When connection is completed from the toll line X (see Fig. 12) to a local line the repeating coil R' is included in the circuit in accordance with standard practice. Suppose, however, that the connection is extended via the toll rotary connector N to the toll line Z. A reference to Fig. 7 will show that the line circuit will now include a repeating coil R² in the selector repeater M². Were it not for some special arrangement we would then have two repeating coils in the connection between the two toll lines at the No. 2 exchange, resulting in an unnecessary transmission loss. Means is accordingly provided in the selector repeater M' (and in all the other selector repeaters) whereby when connection is extended to another toll line the associated repeating coil is automatically cut out of circuit.

The above features of the automatic switches have been mentioned at this time in order that they may be had in mind during the perusal of the detailed specification in which these features and many others will be fully described.

A brief mention should also be made of the switch operating or control circuit which is superimposed on the toll line Z. Referring to Fig. 8, it will be seen that toll line Z is equipped at each end with well known composite telegraph apparatus comprising the toroidal coils T, T', T² and T³, together with the usual arrangement of condensers. Two grounded circuits are thus obtained in addition to the metallic talking circuit. The grounded circuit which includes the lower conductor of toll line Z is shown as a simple Morse telegraph circuit, while the grounded circuit including the upper conductor of toll

line Z is in use as a switch operating circuit, as will be further explained in the detailed specification. Since ringing currents of ordinary frequency cannot be used on composite toll lines without interference, I have indicated by reference characters U and U' two composite ringers, one at each end of the toll line. The purpose and utility of a composite ringer in this connection is well known and need not be explained in detail. Reference is had to U. S. Letters Patent No. 709,437 granted Sept. 16, 1902 to J. M. Fell.

The operator's cord circuits, one of which is shown in Fig. 3, are designed especially for automatic long distance work and include several features, thought to be new, which relate to control of supervision and other details and which will be fully explained hereinafter. The reference character S indicates a calling device or impulse sender which is similar to the substation calling devices.

Throughout the drawings I have shown a plurality of batteries B', B², etc., for supplying operating and talking current. It is to be understood, however, that in accordance with the usual practice there is preferably but one battery in each exchange, having its positive pole grounded. An exception to the above are the batteries for supplying current to the toll line switch control circuits. There is provided in each exchange in addition to the regular exchange battery a special battery or generator of approximately double the voltage of the exchange battery. These special batteries are the battery B⁵ (Fig. 4), batteries B⁸ and B¹⁵ (Figs. 5 and 7) and battery B²² (Fig. 9). Each exchange is also provided with a busy signaling machine such as is indicated by reference character Q (Fig. 1); a ringing current generator such as generator Gen' (Fig. 1); and intermittent ringing apparatus such as is indicated by reference characters I R (Fig. 1).

Having described briefly the general layout of the system and the character of the apparatus involved, I will now proceed to explain in a more detailed manner the operation of the circuits. For this purpose it will be assumed that the subscriber at substation A (Fig. 1) desires to obtain connection with the subscriber at substation A⁸ (Fig. 11), this being the complete circuit connections shown in the drawings and previously referred to.

In order to initiate a long distance call the subscriber at substation A must get into communication with a so called recording operator at his exchange, which is the No. 1 exchange. Any approved method of accomplishing this object will serve but since the substation A is an automatic substation it will be assumed that the subscriber calls the operator automatically as follows: Upon

removing the receiver at substation A, the line switch C is operated to extend the line conductors 12 and 13 through to a selector switch, which may be the selector to which the trunk conductors 14, 15, and 16 extend. After the line switch has operated, the subscriber may manipulate the finger hole dial of his instrument in accordance with the digit 0, thereby operating the selector to select a group of trunks extending to a recording operator's position; after which the selector rotates its wipers automatically to connect with an idle one of these trunks, all in a well known manner. The calling subscriber, upon hearing the operator respond, will give her the necessary information, such as the name and address of the person with whom conversation is desired, and also his own name and telephone number; and will then replace his receiver, thereby restoring the line switch C and the selector switch to normal position. The recording operator in the meantime will write out the data received from the subscriber on a ticket, which is passed to a toll operator whose duty it is to complete the required connection.

In the case under consideration the wanted subscriber is located in the No. 3 exchange which must be reached via the No. 2 exchange. The toll operator, therefore, after first observing that the toll line X extending to the No. 2 exchange is idle, as indicated by the unlighted condition of busy lamp L³, inserts the calling plug of the cord circuit shown in Fig. 3 in the jack J'. By the insertion of the plug in the jack the following circuit is completed over the sleeve of the cord: ground at G², armature 34 and resting contact, resting contact of armature 34 and the said armature, winding 28 of relay 27, contact springs 33 and 32 of key K³, sleeve of plug, sleeve of jack J', conductor 102, resting contact of armature 112 and the said armature, and winding of relay 113 of the selector repeater M to battery B⁴. Relay 27 in the cord circuit is marginal and is not operatively energized by current flow in the above circuit. Relay 113, however, is operated and by means of its armature 115 closes a circuit from ground G⁶ which includes the winding of slow acting relay 114 and battery B⁴. Upon energizing, relay 114 by means of its armature 117 removes ground from the resting contact of armature 116 of relay 113, and by means of its armatures 118 and 119 closes circuits for the busy lamp L³ and the cut off relay 104. The first of these circuits may be traced as follows: ground at G⁷, armature 118 and its working contact, conductor 101, and the busy lamp L³ to battery B². Multiple busy lamps in other operators' positions are also lighted in parallel with busy lamp L³. A four

- conductor trunk line, which may be considered an extension of toll line X , is indicated by reference character 140 (Fig. 3), and extends (when the No. 1 exchange is 5 equipped as a switching exchange) to multiple contacts in the banks of toll rotary connectors such as the connector N (Fig. 6). It will be seen that a branch of conductor 101 extends to test contact 106 and 10 its multiples where by a ground potential on these test contacts the toll line X is made busy. Returning to the relay 114, the circuit for the cut-off relay extends as follows: ground at G^8 , working contact of 15 armature 119 and the said armature, conductor 105, and the winding of cut off relay 104 to battery B^3 . By the operation of the cut-off relay the drop 103 is disconnected in the usual manner.
- 20 When the relay 113 was energized over the sleeve of the cord, a switch control circuit extending to the No. 2 exchange was completed, which for convenience may be traced in reverse direction as follows: 25 battery B^5 , resistance r , working contact of armature 116 and the said armature, winding of relay 120, windings 122 and 123 of repeating coil R in parallel, contact springs of relay 124, line conductors of toll 30 line X in parallel, contact springs 233 and 234 of relay 224 and their resting contacts, windings 222 and 223 of repeating coil R' in parallel, winding of relay 220, armature 216 of relay 213 and its resting contact, and armature 217 of relay 214 and its resting contact to ground at G^{10} . Upon the closure of the above circuit relay 120 of the selector repeater M and relay 220 of the selector repeater M' are operated. The energization 35 of relay 120 is without effect for by the operation of relay 114 ground G^7 has been disconnected from the armature 121 of the said relay 120.
- 40 The relay 220 of selector repeater M' , however, operates to complete the following circuit: ground at G^{11} , armature 218 and its resting contact, armature 237 and its working contact, and the winding of relay 226 to battery B^6 . Upon attracting 45 its armature 254, relay 226 short-circuits the condenser 255. This operation is of no particular consequence in the connection now being established and may be for the present neglected. A further result of the 50 energization of relay 226 is the closure of a circuit for slow acting release relay 227 as follows: ground at G^{12} , armature 238 and its working contact, and winding of relay 227 to battery B^7 . Upon energizing, 55 relay 227 prepares by means of its armature 241 a circuit for the vertical magnet 232 in the usual manner, and in addition closes a busying circuit as follows: ground at G^{14} , armature 240 and its working contact, conductor 201, and the busy lamp L^4 (Fig. 6)
- and its multiples at the toll board in the No. 2 exchange. A branch of conductor 201 extends by way of a conductor of trunk 240 to test contact 206 and its multiples in the banks of toll rotary connectors N and N' 70 and other similar connectors where by a ground potential on these test contacts the toll line X is made busy.
- 75 The foregoing operations have all occurred in response to the insertion of the plug in jack J' at the No. 1 exchange. At this point it should be noted that while the toll line X has been made busy to the operators and to the toll rotary connectors in the No. 2 exchange, the cut off relay 204 has not been 80 operated to disconnect the drop 203. It follows then that if she so desires, the operator at the No. 1 exchange may signal the distant operator manually by throwing her ringing key K^2 to project generator current out over 85 the toll line to actuate the drop 203.
- 90 We have assumed, however, that the connection under consideration is to be established automatically and, such being the case, the toll operator will proceed by operating her calling device key K^3 , whereby through the shifting of contact spring 32 from engagement with contact spring 33 into engagement with contact spring 36 the calling device S is substituted for the relay 27 in the 95 circuit of relay 113 of selector repeater M . At this time also the listening key K' should be in operated position whereby the operator's head set P is bridged across the tip and ring strands of the calling end of the cord 100 circuit. Since the talking circuit is independent of any operating circuit and is kept clear, section after section, as fast as established, a trained operator is able, while operating her calling device, to judge of the 105 correct response of the switching apparatus by certain characteristic sounds in her receiver. Especially is this true in the case of busy signals which are transmitted back to the sending operator from the various 110 switching points in case all outgoing trunks or toll lines of a desired group are busy as will be explained hereinafter. A further feature of the cord circuit which should be mentioned is the fact that the calling device key 115 K^3 , when operated, disconnects the tip and ring conductors of the answering end of the cord circuit. It follows that a subscriber whose line may be connected with by the answering end of the cord is prevented from 120 interfering with or hearing whatever is taking place at the calling end.
- 125 To proceed with the operation, the first digit of the number to be called is the digit 0, for as previously mentioned the tenth bank level of the selector repeaters is the level which is assigned to the toll rotary connector trunks. Accordingly, the operator will now manipulate the dial of the calling device S in accordance with the digit 0, 130

thereby interrupting ten times the circuit of relay 113 of the selector repeater M (Fig. 4). In response to these interruptions of its circuit, relay 113 is deenergized a corresponding number of times, interrupting at each deenergization the previously described control circuit which includes the relay 220 of selector repeater M' (Fig. 5) at the distant exchange. It follows that relay 220 is likewise deenergized ten times to cause a series of interruptions in the circuit of relay 226.

At each interruption of its circuit relay 226 in turn is deenergized momentarily and sends an impulse from ground G¹³ through spring 238 and its back contact, spring 241 and its front contact, spring 271 and its back contact, and the winding of slow acting relay 228 and the winding of the vertical magnet 232 in series. The vertical magnet, in response to these impulses, operates to step up the shaft of the selector repeater M' until the wipers 245, 246, 247, and 248 arrive at the tenth horizontal level of bank contacts. Relay 228 is energized in series with the vertical magnet and being slow acting retains its armature attracted during the series of impulses. At the first upward movement of the shaft a circuit for the cut off relay 204 (Fig. 6) is closed as follows: ground at G¹⁵, off normal contact 260, conductor 205, and the winding of cut off relay 204 to battery B¹⁰. The operation of the cut off relay disconnects the drop 203 in the usual manner. An additional circuit closed upon the first upward movement of the shaft, is an energizing circuit for the relay 230, which extends from ground G¹⁴ by way of the armature 240 and its working contact, armature 263 and its working contact, off normal contact 262, and the winding of relay 230 to battery B¹¹. Upon energizing, relay 230 locks itself independent of relay 228 by means of its armature 264, and by means of its armature 265 prepares a circuit for the rotary magnet 231 which is held open by the relay 228 during the vertical operation of the switch. At this point it should be mentioned that by the closure of the off normal contact 262 the line switching relay 243, whose lower terminal is connected to ground G¹⁴, is connected in series with the relay 230, the circuit passing through interrupter contact 266 of the rotary magnet. The junction point 267, however, has already been connected to ground as previously mentioned so that the relay 243 is short-circuited and remains inoperative for the present.

When the slow-acting relay 228 deenergizes at the end of the series of impulses, it completes at the resting contact of its armature the previously mentioned circuit of the rotary magnet, extending from ground G¹⁴. Upon energizing, the rotary magnet operates to rotate the wipers 245,

246, 247, and 248 into engagement with the first set of bank contacts in the horizontal level to which they have been raised. Near the end of its stroke the rotary magnet opens the interrupter contact 266, thereby breaking the locking circuit of relay 230. Upon deenergizing, the relay 230 breaks the energizing circuit of the rotary magnet, which magnet accordingly retracts its armature to again close the interrupter contact 266. The operation now depends on whether the first toll rotary connector trunk line, the terminals of which are now engaged by the selector repeater wipers, is busy or not. Assuming that this trunk line is busy, the test contact upon which the test or private wiper 247 is resting will have ground potential upon it, which ground potential will serve to maintain the line switching relay 243 short-circuited and also to again energize the relay 230. It should be mentioned here that the relay 242, which is in series with the private wiper 247, is of very low resistance in order that the relay 243 may be effectively short-circuited, and is made slow to energize by means of a slug of copper in order that it may not energize from momentary impulses received during the testing of busy trunk lines. Returning to the relay 230, when this relay is energized over the private wiper, as previously described, the energizing circuit of the rotary magnet is again closed, whereby the same cycle of operations is repeated. It will be seen then that the relay 230 will operate as an interrupter to step the switch wipers around through the medium of the rotary magnet as long as the test wiper 247 engages busy or grounded test contacts. When an idle or ungrounded test contact is reached and the rotary magnet retracts its armature the relay 230 cannot again energize. The switching relay 243, however, being no longer short-circuited, at once energizes in series with the said relay 230. Relay 243 is of such high resistance that the relay 230 remains inoperative. Upon energizing, the switching relay 243 opens at its armature 270 the circuit for the vertical magnet 232; shifts by means of its armature 275 the private wiper 247 from its normal connection to junction point 267 into connection with the grounded conductor 201; disconnects at its armature 272 the conductor 202 from the winding of relay 213; extends the heavy line conductors by way of its armatures 273 and 274, line wipers 245 and 248, and trunk conductors 301 and 304 to the toll connector N (Fig. 6); and finally, by means of armature 271, completes a control circuit including the line relay 307 of the toll rotary connector N (Fig. 6); which may be traced as follows: ground at G¹³, armature 289 and its working contact, the said armature 271 and its working contact,

wiper 246 and the bank contact engaged thereby, conductor 302, armature 317 and its resting contact, and the winding of line relay 307 to battery B¹².

5 Upon the closure of the above circuit, relay 307 is energized and by means of its armature 326 completes a circuit for the slow-acting release relay 308. Relay 308, upon attracting its armature 329, prepares 10 a circuit for the vertical magnet 318 in the usual manner. It should be noted here that trunk conductor 303, extending from the test contact 352 is not grounded by the release relay 308 as is customary. Instead, 15 the test contact 352 and its multiples are maintained at ground potential, or nearly so, over the path which extends from ground G¹⁴ by way of armature 240 of relay 227, conductor 201, working contact of 20 armature 275 and the said armature, winding of low resisting relay 242, and the private wiper 247. The toll connector N is thus made busy to other selector repeaters. Since relay 242 is slow to 25 energize, as already explained, it will not be operated by momentary current impulses due to other selector repeaters passing over the now busy multiple terminals of the trunk line extending to the toll rotary connector N.

The operator is now ready to call the digits necessary to actuate the connector N, whereby an idle toll line extending to the No. 3 exchange may be selected. In Fig. 13 35 is shown the lower or first bank level of one of the toll rotary connectors, it being assumed that this is the level in which the toll lines extending to the No. 3 exchange terminate. As previously mentioned, each level 40 may contain more than one group of toll lines, and the first three sets of contacts, therefore, may be terminals of toll lines extending to the No. 1 exchange. The next set of contacts is connected to a trunk line 45 comprising the conductors 341, 342, and 343, which extend to the jack J' at a toll operator's position. The next four sets of contacts may be the terminals of the group of toll lines extending to the No. 3 exchange, 50 the toll line Z being the second toll line in the group. The next contact set, as before, is connected to the trunk line extending to the jack J'. It will be understood that other groups of toll lines may be terminated 55 in the remaining levels of the toll rotary connectors in a similar manner, the next contact set after each group being connected as already explained. From the foregoing, it will be understood that since the toll lines 60 extending to the No. 3 exchange are terminated in the first level of the toll rotary connectors, and since the first one of these toll lines terminates in the fifth contact set of this level, the proper digits to be called now 65 are the digits 1 and 5.

The operator at the No. 1 exchange, therefore, will now operate her calling device in accordance with the digit 1, thereby causing as before a momentary deenergization of the relay 113 of the repeater M. In 70 response to this momentary deenergization an interruption is produced in the control circuit extending to the relay 220 of the selector repeater M' at the No. 2 exchange. Relay 220 thereupon deenergizes momentarily 75 to interrupt the circuit of relay 226, which relay in turn produces a momentary interruption of the circuit of the line relay 307 of the toll rotary connector N. Responsive to this interruption of its circuit, relay 80 307 deenergizes momentarily and transmits an impulse from ground G¹⁶ to the slow-acting relay 309 and the vertical magnet 318 in series, side switch wiper 320 being in its first position. In response to this impulse 85 the vertical magnet operates to step up the switch shaft until the wipers 345, 346, 347, and 348 stand opposite the first horizontal level of bank contacts. Relay 309 is energized in series with the vertical magnet 318 90 and closes by means of its armature 328 a circuit which extends from ground G¹⁷ to the winding of relay 310 and the winding 316 of the private magnet 314 in parallel. The resultant energization of relay 310 is of 95 no consequence at this present time. The momentary operation of the private magnet 314, however, effects the movement of the side switch wipers 320, 321, to their second position in the usual and well understood manner.

The operator may now manipulate her calling device in accordance with the digit 5, thereby again producing a series of interruptions in the circuit of relay 113 of the 105 selector repeater M. As before these interruptions are repeated through the medium of relays 220 and 226 of the selector repeater M' until they finally effect the circuit of line relay 307 of toll rotary connector N and 110 cause five deenergizations of the said relay. At each deenergization, relay 307 sends an impulse from ground G¹⁸ to the slow-acting relay 309 and the rotary magnet 319 in series, side switch wiper 320 being in its second position. In response to these impulses the rotary magnet operates to rotate the wipers 345, 346, 347, and 348 until they arrive at the 5th set of contacts of the first level. Relay 309 is energized in series with 115 the rotary magnet 319 and being slow-acting, retains its armature during the series of impulses to close the energizing circuits of the relay 310 and the private magnet 314. At the end of the series of impulses, 120 relays 309 and 310 and private magnet 314 deenergize (it being assumed that the 5th contact set is idle), the private magnet controlling the side switch wipers 320 and 321 to advance them to their third position. 125 130

We will assume, however, that the 5th contact set is busy and that the 6th contact set, which is the contact set in which the toll line Z extending to the No. 3 exchange 5 terminates, is idle. Under these circumstances the test contact of the 5th contact set, with which the private wiper 347 is now in engagement, will have ground potential upon it and the private magnet 314 will be 10 maintained energized over the following circuit: ground on busy test contact, private wiper 347, side switch wiper 321 in the second position, and winding 315 of private magnet 314 to battery B¹³. The private 15 magnet being held energized and its armature 322 being in engagement with its working contact, as soon as the relays 309 and 310 deenergize a new energizing circuit is completed for the rotary magnet 319 which 20 may be traced as follows: ground at G¹⁷, armature 328 and its resting contact, resting contact of armature 331 and the 25 said armature, armature 332 and its working contact, armature 334 and its resting contact, winding of rotary magnet 319, and the side switch wiper 320 in second position to battery B¹⁴. Upon the closure of 30 the above circuit the rotary magnet 319 operates to step the wipers 345, 346, 347 and 348 into engagement with the 6th contact set. Near the end of its stroke the rotary magnet 319 closes by means of its armature 323 the circuit of relay 310, which relay upon energizing, breaks the last described 35 energizing circuit of the rotary magnet by means of its armature 331. The rotary magnet accordingly retracts its armature 323 and breaks the circuit of relay 310, which relay, upon deenergizing allows 40 its armature 331 to again engage its resting contact. The energizing circuit of the rotary magnet is not again closed, however, for the private magnet 314 has already deenergized, the test contact 406 of the 45 6th contact set being ungrounded, and opened the rotary magnet circuit at its armature 332. The wipers of the toll rotary connector N have now been brought to rest in engagement with the 6th contact set, which 50 contact set is a multiple terminal of the toll line Z extending to the No. 3 exchange, and the side switch wipers of the toll rotary connector have been advanced to their third 55 positions.

By the movement of side switch wiper 321 to its third position, a circuit is closed for the busy lamp L⁵ (Fig. 7) and its multiples, which extends as follows: ground at G¹⁸, side switch wiper 321 (in third position), 60 wiper 347, test contact 406, conductor 401, and the lamp L⁵ to battery B²⁰. A branch of the above circuit (not shown) extends to multiple test contacts similar to test contact 406 in the banks of the other toll rotary connectors, where by a ground poten-

tial on the said test contacts, the total line Z is made busy.

By the advance of side switch wiper 320 to its third position, a circuit is closed which includes the switching relay 312 and the relay 242 of the selector repeater M'. This circuit may be traced as follows: ground at G¹⁴, armature 240 and its working contact, conductor 201, working contact of armature 275 and the said armature, winding of relay 242, private wiper 247, bank contact 352, conductor 303, winding of relay 312, and the side switch wiper 320, in third position, to battery B¹⁴. Relay 312 of the toll rotary connector N and relay 242 of the selector repeater M' are therefore energized in series.

Considering first the function of relay 242, this relay, upon energizing, closes a circuit for relay 224 as follows: Ground at G¹², armature 244 and its working contact, and the winding of relay 224 to battery B¹⁷. Upon energizing, relay 224 disconnects its armatures 235 and 236 from their respective resting contacts and brings them into engagement, respectively, with contact springs 233 and 234, the said springs being thereby disengaged from their respective resting contacts. By this operation the heavy line conductors are connected straight through, the repeating coil R' being eliminated from the line circuit. Two of the repeating coil windings, the windings 222 and 223 are left in bridge of the line circuit in order that the simplex control circuit including the relay 220 may be maintained. The retardation coil 225 is included in the bridge to increase its impedance and to thereby prevent excessive transmission loss.

Returning now to the relay 312 of the connector N, which relay it will be remembered, was energized in series with the relay 242, the following operations were performed as a result of its energization: At the resting contact of armature 339 a conductor extending to the release magnet 313 is opened to provide against the energization of said release magnet upon the deenergization of line relay 307 and release relay 308; by the engagement of armatures 337 and 338 with their working contacts the incoming line conductors are extended through to selector repeater M² (Fig. 7) by way of line wipers 345 and 348; and finally, by means of armature 317, conductor 302 is disconnected from the winding of the line relay 307 and is extended to the line relay 413 of the selector repeater M² over the following path: conductor 302, armature 317 and its working contact, wiper 346 and the contact engaged thereby, conductor 402, resting contact of armature 412 and the said armature, and the winding of relay 413 to battery B¹⁸. Upon energizing, relay 413 completes a circuit extending from ground G²⁰ and including the winding of slow-acting 130

relay 414 and the battery B^{18} . Upon energizing in turn, relay 414 disconnects ground G^{23} from the resting contact of armature 416 of the line relay 413, and in addition, connects ground G^{21} to the conductor 401. The latter operation, however, is of no particular consequence just now, since conductor 401 has already been grounded by way of the private wiper 347 of the rotary connector N. As a further result of the energization of relay 414, ground G^{22} is connected to the conductor 405, whereby the cut-off relay 404 is operated to disconnect the drop 403.

When the relay 413 was operated a control circuit extending to the No. 3 exchange was completed, which may be traced from the negative pole of battery B^{15} as follows: battery B^{15} , resistance r' , working contact of armature 416 and the said armature, relay 420, conductor 480, winding 481 of toroidal coil T', winding 483 of the said coil, upper line conductor of toll line Z, winding 484 of toroidal coil T², winding 485 of the said coil, conductor 486, relay 520, armature 516 of relay 513 and its resting contact, armature 517 of relay 514 and its resting contact to ground at G^{24} . Upon the closure of the above circuit relay 420 of the selector repeater M² and relay 520 of the selector repeater M³ are energized in series. The operation of relay 420 produces no effect for ground G^{21} has been disconnected from the armature 421 by the operation of the slow-acting relay 414.

The toll selector repeater M³ is almost exactly like the toll selector repeater M' and its operation will, therefore, be described in a somewhat cursory manner. When the relay 520 is energized over the control circuit from the No. 2 exchange, an energizing circuit is completed for the relay 526, which relay, upon its operation, completes an energizing circuit for the slow-acting relay 527. By the attraction of its armature 541, relay 527 prepares a circuit for the vertical magnet 532 in the usual manner, and by the attraction of its armature 540 closes a circuit for the busy lamp L⁶ as follows: ground at G^{54} , armature 540 and its working contact, conductor 501, and the lamp L⁶ to battery B^{21} . A branch of the above circuit extends to the test contact 506 and its multiples in the banks of the toll rotary connectors in the No. 3 exchange (it being assumed that the No. 3 exchange is so equipped) where by a ground potential on these test contacts the toll line Z is made busy. As in the case of selector repeater M', the cut-off relay 504 is not operated until after the selector repeater M³ has made its first movement.

The foregoing operations at the selector repeaters M² and M³ have taken place in response to the seizure of the toll line Z by

the toll rotary connector N. These operations, it will be observed, correspond exactly to the operations at selector repeaters M and M' responsive to the insertion of the plug in jack J'. The operator at the No. 1 exchange is now ready to dial the directory number of the wanted subscriber in the No. 3 exchange, but before proceeding, it will be well to return to the toll rotary connector N and consider its operation in case all the toll lines extending to the No. 3 exchange had been busy. Immediately after the rotation of the connector N responsive to the dialing of the third digit, the relay 309 having deenergized, the test relay 311 is connected in bridge of the line wipers 345 and 348 as follows: wiper 345, armature 370 and its resting contact, armature 325 and its working contact, armature 327 and its resting contact, winding of relay 311, resting contact of armature 338 and the said armature, and the resting contact of armature 371 and the said armature to wiper 348. It will be seen then that during the automatic rotation of the connector wipers in search of an idle toll line the relay 311 will be connected in bridge of the several lines in succession. Since the toll lines are clear of all bridged battery, however, relay 311 is not energized. But on the assumption that all the toll lines extending to the No. 3 exchange are busy, the wipers will finally arrive at the contact set which is connected to the trunk 341, 342, 343. The wipers 345 and 348 are now connected to opposite poles of the battery B^{16} by way of conductors 342 and 341 and the windings of relay 340. It follows that relay 311 is instantly energized in series with relay 340 to stop the rotation of the switch by opening the rotary magnet circuit at its armature 334. At the same time, relay 311 locks its own circuit independent of relays 307 and 309 at its armature 333, and connects the secondary of the transformer of the busy signal machine Q¹ in bridge of the heavy line conductors extending back to the No. 1 exchange. Relay 340 is energized to close the circuit of the lamp L⁷, but ordinarily the operator at the No. 2 exchange does not get time to answer, for the No. 1 exchange operator, perceiving the busy signal, will release the connection at once. In case, however, the busy signal is received several times in succession the No. 1 exchange operator may want to inquire as to the probable length of time the toll lines will be tied up, and will therefore wait on the line. Observing the continued lighting of lamp L⁷ the No. 2 exchange operator will answer by plugging into jack J'. By the insertion of the plug ground is removed from conductor 343, whereby the private magnet 314 of the connector N is allowed to deenergize to advance the side switch wipers to third position. Re. 130

lay 312 is then operated to connect through the heavy line conductors and the operators may converse as desired.

Returning now to the selector repeater 5 M^3 (Fig. 9), we will proceed with the establishment of the connection. By manipulating her calling device S in accordance with the first digit in the directory number of the subscriber in the No. 3 exchange, 10 the operator at the No. 1 exchange again produces a series of interruptions in the circuit of the relay 113 of the selector repeater M . These interruptions are repeated through the medium of the relay 113, relays 220 and 15 226 of the selector repeater M' , relay 413 of the selector repeater M^2 and the relay 520 of the selector repeater M^3 until they finally effect the circuit of relay 526. Responsive to these interruptions of its circuit 20 relay 526 deenergizes a number of times and sends at each deenergization an impulse from ground G^{25} through the slow-acting relay 528 and the vertical magnet 532 in series. The vertical magnet 532 is accordingly 25 operated to step up the switch shaft until the wipers 545, 546, 547 and 548 stand opposite the horizontal level of bank contacts in which terminate trunk lines extending to the desired main group of subscribers' 30 lines. Upon the first upward movement of the switch shaft, an energizing circuit for the cut-off relay 504 is established which extends from ground G^{26} by way of the shaft controlled off-normal contact 560 and 35 conductor 505. The operation of the cut-off relay 504 disconnects the drop 503 from the line. Relay 528 is energized in series with the vertical magnet 532 and being slow-acting, retains its armature during the 40 series of impulses. An additional circuit closed upon the first upward movement of the shaft is an energizing circuit for the relay 530, which is controlled jointly by the off-normal contact 562 and the relay 528. 45 Upon energizing, relay 530 establishes a locking circuit for itself by means of its upper armature, and at its lower armature prepares a circuit for the rotary magnet 531 which is held open during the vertical 50 operation of the switch by the relay 528. As described in the case of selector repeater M' , the switching relay 543 is now connected in series with the relay 530, but being short-circuited, remains inoperative for 55 the present. When the relay 528 deenergizes at the end of the series of impulses, it completes the previously mentioned circuit of the rotary magnet 531, whereby the wipers 545-548, inclusive, are started rotating 60 in search of an idle trunk line.

The contact sets in the bank level over which the wipers of the selector repeater are now rotating are terminals of trunk lines extending to toll second selectors, one of 65 which may be toll second selector W^3 (Fig.

10). Assuming that the first idle or ungrounded test contact in this level is the test contact 600, when the private or test wiper 547 arrives at this test contact the rotation of the switch will be stopped, and the switching relay 543 will energize in series with the relay 530, all as previously described in discussing the operation of the selector repeater M' (Fig. 5). Upon energizing, relay 543 performs the following switching operations: By means of armature 575 the private wiper 547 is connected with the grounded conductor 501; at the resting contact of armature 570 the circuit of the vertical magnet 532 is opened; at the resting contact of 70 armature 572 the conductor 502 is disconnected from the winding of relay 513; by means of armatures 573 and 574 the upper and lower heavy line conductors are connected, respectively, to line wipers 545 75 and 548; and finally, at armature 571, a control circuit is completed which extends through the line relay 626 of the toll second selector W^3 (Fig. 10) and which may be traced over the following path: ground at 80 G^{25} , armature 541 and its working contact, armature 571 and its working contact, wiper 546 and the contact engaged thereby, conductor 602, armature 650 and its resting contact, and the winding of relay 626 to battery B^{23} . The line relay 626 is energized over the above circuit and completes at its 85 upper armature 638 a circuit for the slow-acting relay 627. Relay 627, upon energizing in turn, prepares by means of its lower 90 armature 641 a circuit for the vertical magnet 632, and at upper armature 640 connects ground G^{27} to the trunk conductor 603. It is to be noted that test contact 600 95 and its multiples have already been grounded by way of the private wiper 547 of selector repeater M^3 , winding of relay 542, and grounded conductor 501, whereby the trunk line extending to the toll second selector W^3 is made busy. It will appear then, that the 100 grounding of conductor 603 at this time is superfluous. This is, in fact, the case when connection is extended to the selector W^3 by way of a selector repeater such as the selector repeater M^3 . When, however, the toll 105 second selector W^3 is seized by a toll first selector such as V^3 , the private wiper of which is not connected to ground after the switch has operated, as will be presently explained, the reason for grounding conductor 110 603 will be clear.

The operator at the No. 1 exchange may now call the second digit of the desired number. As before a series of interruptions are produced in the circuit of the relay 113 of 115 the selector repeater M which are repeated in the manner already described to cause a series of deenergizations of the relay 526 of the selector repeater M^3 . At each retraction of its armature 541 the relay 526 120 125 130

interrupts the circuit of the line relay 626 of the toll second selector W^3 . In response to these interruptions of its circuit relay 626 deenergizes a number of times, and at 5 each retraction of its armature sends an impulse from ground G^{28} through the winding of slow-acting relay 628 and the vertical magnet 632 in series. Through the medium of the vertical magnet, the wipers 645-648, 10 inclusive, are raised, step by step, until they stand opposite the horizontal level of bank contacts in which terminate trunk lines extending to the desired sub-group of subscribers' lines. The relay 628 is energized in series with the vertical magnet 632 and being slow-acting retains its armature during the series of impulses. As soon as the off-normal contact 662 is closed by the upward movement of the shaft an initial 15 energizing circuit is completed in the usual manner for the relay 630. Upon energizing, relay 630 establishes a locking circuit for itself at its lower armature, and at its upper armature prepares a circuit for the rotary magnet 631. The switching relay 643 is short-circuited as usual and remains inoperative for the present.

When the slow-acting relay 628 deenergizes at the end of the series of impulses, 20 the previously mentioned circuit of the rotary magnet 631 is closed, and the wipers 645-648, inclusive, start rotating in search of a trunk line extending to an idle connector switch. Assuming that the trunk line 25 terminating in the connector switch H^3 (Fig. 11) is the first trunk line which is idle, when the private wiper 646 arrives at the test contact 700, the rotation of the selector wipers will be stopped, and the switching relay 643 will be energized in series with the relay 630. Upon energizing, the switching relay 643 performs the following operations: At the resting contact of armature 670 the circuit of the vertical magnet 632 30 is opened; by means of armature 675 the private wiper 646 is disconnected from the circuit of relay 643 and is connected instead by way of the armature of A. C. relay 680 to battery B^{25} for a purpose to be described hereinafter; by means of armatures 673 and 35 674 the double-wound relay 660 is connected in bridge of the line wipers 645 and 648; and finally, through the engagement of armature 671 with its working contact, a control circuit is completed for the line relay 726 of the connector H^3 (Fig. 11) which 40 extends over the following path: ground at G^{28} , armature 639 and its working contact, working contact of armature 671 and the 45 said armature, resistance r^8 , wiper 647 and the contact engaged thereby, conductor 702, normally closed contact springs of the back bridge relay 718 and the upper winding of line relay 726 to battery B^{26} . Upon energizing, 50 relay 726 completes an energizing

circuit for the slow-acting relay 727, which relay, upon energizing in turn, prepares at its armature 741 a circuit for the vertical and rotary magnets in the usual manner, and at its upper armature 740 connects ground 70 G^{31} to the conductor 701, whereby the following circuit is completed: ground G^{31} , armature 740 and its working contact, conductor 701, winding of relay 751, winding of relay 752, conductor 703, contact 700, 75 wiper 646, armature 675 and its working contact, armature 676 and its resting contact, and resistance r^2 to battery B^{25} . Upon the closure of the above circuit, relays 751 and 752 are energized in series. Relay 752 80 is a ringing relay which is controllable by the operator in a manner to be described hereinafter. Relay 751 is a switching relay whose operation alters the circuits of the connector in such a manner that its characteristics are changed from those of a local connector to those of a toll connector. These switching operations can best be understood from a comparison of the operation of the connector H^3 as a toll connector with its operation as a local connector.

To proceed, relays 751 and 752 are of very low resistance whereby the test contact 700 and its multiples are brought sufficiently near to ground potential to render connector H^3 busy to other toll second selectors. A branch of conductor 701 extends to multiple test contacts, such as the test contact 707, in the banks of the local second selectors, such as the second selector F for example, 100 rendering the connector H^3 busy to the local second selectors also.

The operator at the No. 1 exchange may now call the third digit in the number of the wanted subscriber thereby once more 105 producing a series of interruptions in the circuit of the relay 113 of the selector repeater M. As before, these interruptions are repeated until they are finally reproduced in the circuit of the line relay 626 of the toll 110 second selector W^3 . The line relay 626 is accordingly deenergized a number of times to repeat the interruptions of its circuit into the circuit of the line relay 726 of the connector H^3 . In response to these interruptions of its circuit the line relay 726 is deenergized a number of times, and at each deenergization sends an impulse from ground 115 G^{28} through the winding of the slow-acting relay 728 and the winding of the vertical 120 magnet 732 in series, side switch wiper 770 being in its first position. In response to these impulses the vertical magnet 732 operates to raise the wipers 745, 746, and 748 until they stand opposite the horizontal bank 125 level in which are located contacts which are terminals of the line of substation A^3 . The relay 728 is energized in series with the vertical magnet and being slow-acting, retains its armature during the series of im- 130

pulses to close an energizing circuit for the private magnet 756. At the end of the series of impulses relay 728 and the private magnet 756 are deenergized, the latter controlling the side switch wipers 770 and 771 to advance them to their second position in the usual manner.

The operator at the No. 1 exchange may now call the final digit in the desired number, resulting as just explained in a series of deenergizations of the line relay 726. Now however, since the side switch wiper 770 is in its second position, the line relay at each deenergization transmits an impulse through the slow-acting relay 728 and the rotary magnet 731 in series. The rotary magnet 731 is thereupon actuated to rotate the wipers 745, 746, and 748 until they are brought to rest upon the set of contacts in which the line of substation A³ terminates. As before, the slow-acting relay 728 and the private magnet 756 are energized during the series of impulses, the latter, upon deenergizing, controlling the side switch wipers 770 and 771 to advance them to their third position (it being assumed that the line of substation A³ was idle when called). Upon the engagement of side switch wiper 771 with its third position contact point, a locking circuit for relay 751 is completed by way of the cut-off winding of line switch C' as follows: ground at G³¹, conductor 701, winding of relay 751, working contact of armature 764 and the said armature, side switch wiper 771 (in third position), wiper 746, test contact 22', and the cut-off winding 17' of line switch C' to battery B³⁰. By the operation of the cut-off armature of the line switch C', responsive to the closure of the above circuit, the line conductors 12' and 13' are disconnected from their normal connections in the line switch. Ground G³¹ also extends to multiple test contacts similar to test contact 22' in the banks of other connectors of the group, thereby making the line of substation A³ busy. As a further result of the advance of the side switch wipers to their third position, a circuit has been closed for the wiper switching relay 753, which may be traced as a branch of the above circuit over the following path: junction point 790, winding of relay 753 and side switch wiper 770 (in third position) to battery B³¹. By the operation of relay 753 the heavy line conductors are extended through to the line wipers 745 and 748.

Connection has now been established with the line of the wanted subscriber in the No. 3 exchange. It is to be noted, however, that this connection is still open at one point. Referring to Fig. 10, the heavy line conductors incoming to the toll second selector W³ terminate, respectively, in the armatures 651 and 652 of relay 660; while the heavy line conductors outgoing from the

toll second selector W³ terminate in the working contacts of these armatures, the relay 660 being as yet deenergized. This relay is, however, connected in bridge of the called subscriber's line in series with the battery B²³ in readiness to be energized upon the removal of the receiver.

The operator at the No. 1 exchange may now restore her calling device key K³. The next operation is the signaling of the called subscriber which takes place in the following manner: A source of ringing current is connected in bridge of the heavy line conductors upon the operation of the ringing key K². By the well known inductive action in repeating coil R (Fig. 4), this ringing current is enabled to operate the A. C. relay 306 connected at the No. 2 exchange in bridge of the heavy line conductors of the toll rotary connector N (Fig. 6). Upon energizing, relay 306 closes the following circuit: ground at G¹⁴, working contact of armature 324 and the said armature, winding of relay 322, and the side switch wiper 320 (in third position) to battery B¹⁴. By the operation of relay 322, the ringing current generator Gen is connected in bridge of the line wipers 345 and 348, resulting in the transmission of ringing current by inductive action in repeating coil R² (Fig. 7) to the composite ringing equipment U (Fig. 8). The apparatus U operates in the well known manner to project a high frequency alternating current out over the line conductors of toll line Z to operate the composite ringing equipment U' at the distant end. The apparatus U' is effective to bridge the ordinary generator current across the heavy line conductors, which current is transmitted by inductive action in the repeating coil R³ to the alternating current relay 680 at the toll second selector W³ (Fig. 10). Upon attracting its armature 676, the A. C. relay 680 disconnects the battery B²⁵ from the previously described circuit over which the relays 751 and 752 of the connector H³ were initially energized. The former of these relays is now being supplied with current through the winding of relay 753 and the cut-off winding of line switch C' is parallel, as explained, and consequently remains energized. The relay 752, however, deenergizes and thereby connects the grounded generator Gen² in bridge of the called subscriber's line in the usual manner. It will be seen then that each time the operator at the No. 1 exchange actuates her ringing key K² various agencies are brought into play to finally effect the deenergization of relay 752 in the connector H³, whereby ringing current is projected out over the called subscriber's line to operate the signal in bridge thereof.

When the called subscriber removes his receiver in response to the ringing of his bell, 130

the relay 660 of the toll second selector W^3 is energized over the two conductors of the called line in series with results as follows: At armature 653 the control circuit extending to the connector H^3 is grounded to provide against the deenergization of relay 626; by means of armature 650 the conductor 602 is switched from connection with the winding of relay 626 to the winding of relay 627 (of no importance in this particular instance); and by means of armatures 651 and 652 the heavy incoming line conductors are disconnected from the bridged A. C. relay 680 and are joined, respectively, to the heavy outgoing line conductors, whereby the through connection to the called line is finally established.

Connection to the desired party having been obtained, the operator at the No. 1 exchange may now proceed to connect with the subscriber who originated the call. To this end the answering plug of the cord circuit in use is inserted in the jack J of the toll service trunk assumed to be idle at the time. By the insertion of the plug in the jack, a control circuit for the line relay 807 of the selector V' is completed as follows: ground at G^3 , winding of relay 25, contact springs 37 and 38 of key K^4 , sleeve of plug, sleeve of jack J , contact springs 805, conductor 802', armature 815 and its resting contact, and the winding of relay 807 to battery B^{35} . Upon the completion of the above circuit, relays 25 and 807 are energized in series. Considering first the operation of relay 25, at its lower armature the ring down relay 26, in permanent bridge of the talking strands of the cord, is greatly reduced in resistance by having its lower winding 31 cut out of circuit. The reason for this will be discussed later. At the upper armature of relay 25 a circuit is closed for the supervisory lamp L' .

Proceeding now to the selector V' , when the line relay 807 attracts its armature a circuit is completed in an obvious manner for the slow acting relay 809. Upon energizing, relay 809 prepares at its armature 817 a circuit for the vertical magnet 813, and at its upper armature 816 completes a circuit over which the busy lamp L and its multiples at other operators' positions are illuminated. This circuit may be traced as follows: ground at G^{36} , armature 816 and its working contact, conductor 801, and the said lamp L to battery B^{36} .

The operator may now throw her calling device key K^4 whereby through the shifting of contact spring 38 into engagement with contact spring 39 the calling device S is substituted for the relay 25 in the controlling circuit of the line relay 807 of the selector V' . Relay 25 is thus deenergized temporarily and the lamp L' extinguished. At the same time the calling

end of the cord circuit is cut off in an obvious manner so that the called subscriber at the distant exchange is prevented from overhearing whatever takes place in the No. 1 exchange.

The operator will now proceed to manipulate the dial of her calling device in accordance with the first digit in the number of the subscriber at substation A, whereby a series of interruptions are produced in the circuit of the line relay 807 of the selector V' . Responsive to these interruptions of its circuit, the line relay 807 is deenergized a corresponding number of times and at each deenergization sends an impulse from ground G^{36} through the windings of the slow acting relay 810 and the vertical magnet 813 in series. In response to these impulses the vertical magnet steps up the switch shaft until the wipers 891-894, inclusive, stand opposite the horizontal level of bank contacts in which are terminated trunk lines extending to toll second selectors in the desired main group of subscribers' lines. The slow acting relay 810 is energized in series with the vertical magnet as usual and completes an energizing circuit for relay 811. Upon attracting its armature 819, the relay 811 locks itself over the following path: ground on conductor 801, armature 819 and its working contact, off normal contact 818 (closed at the first upward movement of the shaft), winding of relay 811, and the interrupter contact of the rotary magnet 812 to battery B^{37} . A branch of the above circuit extending from the resting contact of spring 820 to the rotary magnet 812 is held open by the relay 810 during the vertical operation of the switch. The switching relay 808 as usual is short circuited, its upper terminal being connected to the grounded conductor 801 and its lower terminal being connected at junction point 821 to the previously described locking circuit of relay 811.

When the slow acting relay 810 deenergizes at the end of the series of impulses, the previously mentioned rotary magnet circuit is completed by the engagement of its resting contact by spring 820, whereupon the wipers 891-894, inclusive, are started rotating in search of a trunk line extending to an idle toll second selector. The operation of selecting an idle trunk line is similar to the corresponding operation of the toll selector repeater M already described, the relay 811 being operated intermittently while the private wiper 893 is passing over busy contacts to step the wipers around through the medium of the rotary magnet. The switching relay 808 remains short-circuited and inoperative as long as the private wiper engages busy or grounded test contacts but as soon as the first ungrounded test contact is reached (assumed to be the test contact

800') the relay 811 ceases to operate and the said relay 808 energizes over the following path: ground on conductor 801, winding of relay 808, junction point 821, off normal contact 818, winding of relay 811, and interrupter contact of the rotary magnet 812 to battery B³⁷. Relay 808 is of high resistance in order that relay 811 may not energize. By the operation of relay 808, the private wiper 893 is disconnected from junction point 821 and is connected instead to conductor 801, the vertical magnet circuit is opened, and the conductor 802' is disconnected from the line relay 807 and is extended to the line relay 826 of the toll second selector W' over the following path: conductor 802', armature 815 and its working contact, wiper 892 and contact engaged thereby, conductor 802, armature 850 and its resting contact, and the winding of relay 826 to battery B³⁸. Upon energizing, relay 826 completes an energizing circuit for the slow acting relay 827, which relay, upon energizing in turn, prepares a circuit for the vertical magnet 832 in the usual manner, and also completes a holding circuit extending back to the selector V' as follows: ground at G³⁸, working contact of armature 840 and the said armature, conductor 803, contact 800', wiper 893, and the lower armature of relay 808 and its working contact to conductor 801. Thus the conductor 801 is maintained grounded after the deenergization of relays 807 and 809 in order to retain relay 808 in operated position and to keep the busy lamps illuminated. A branch (not shown) of the above holding circuit extends to multiple test contacts similar to test contact 800' in the banks of other toll first selectors whereby the trunk extending to toll second selector W' is made busy. A second branch of the holding circuit extends via conductor 803 to test contact 809 and its multiples in the banks of toll selector repeaters such as the selector repeater M (Fig. 4).

The operator may now proceed to call the second digit in the number of the subscriber at substation A. Since the toll second selector W' is identical with the toll second selector W³, the operations performed responsive to the dialing of the second digit need not be described in detail. It will suffice to say that under the control of the line relay 826 the second selector W' is operated through the medium of its vertical magnet 832 and its rotary magnet 831 to extend the connection by way of its wipers 845-848, inclusive, to a trunk line terminating in an idle connector switch, assumed to be the connector H' (Fig. 1). After the selector W' has operated, the switching relay 843 is energized to perform, among other functions, the bridging of relay 860 across the line wipers 845 and 848, and the establishment of a controlling circuit for the connector H', which ex-

tends from ground G³⁹ by way of the armature 838 and its working contact, working contact of armature 871 and the said armature, wiper 847 and the contact engaged thereby, conductor 902, normally closed contacts of relay 918, and the upper winding of line relay 926 to battery B⁴⁰.

The line relay 926 is energized by current flow over the above circuit and, upon attracting its armature, closes a circuit for the slow acting relay 927. Relay 927 upon energizing, prepares the usual circuits for the vertical and rotary magnets 932 and 931, and also connects ground G⁴⁰ to conductor 901, whereby the test contact 907 and its multiples in the banks of the local second selectors are brought to ground potential to render the trunk line terminating in the connector H' busy. Ground G⁴⁰ also extends by way of the windings of low resistance relays 951 and 952 and the conductor 903 to the test contact 900 and its multiples in the banks of other toll second selectors similar to the selector W' where the trunk line terminating in connector H' is also made busy. The wiper 846 of the selector W' being in engagement with the test contact 900 a flow of current is set up over conductor 903 to the battery B⁴¹, as described in connection with the toll second selector W³, whereby the relays 951 and 952 are energized.

The operator may now call the remaining two digits in the number, thereby producing two series of interruptions in the circuit of the line relay 926 (the original interruptions being repeated by relay 826). Under the control of the line relay 926, the connector wipers 945, 946, and 948 are raised by the vertical magnet 932 and rotated by the rotary magnet 931 until they are brought to rest, respectively, upon the contacts 21, 22, and 23, which contacts are the ones individual to the line of substation A in the bank of connector H'. After each series of impulses the side switch wipers 970 and 971 are advanced one step under the control of the slow acting relay 928 and the private magnet 956 until they finally engage their third position contact points. Current now flows from ground G⁴⁰ by way of the winding of relay 951 and side switch wiper 971 to the winding of the wiper switching relay 953 and the cut-off winding of line switch C in parallel; whereby the relay 951 is locked up, the relay 953 is energized to connect the wipers 945 and 948 with the associated heavy talking conductors, and the cut-off armature of line switch C is operated to disconnect the line conductors 12 and 13 from their normal connections in line switch C.

Connection has now been established with the line of substation A, and the operator will accordingly restore her calling device key K⁴ thereby cutting out the calling de-

vice S and again including the relay 25 in the sleeve of the cord. The subscriber is signaled as follows: By the operation of key K', ringing current is projected out over the heavy conductors to actuate the bridged A. C. relay 880 at the toll second selector W'. When the relay 880 attracts its armature, battery B⁴¹ is disconnected from the energizing circuit of relay 952 of the connector H', whereby the said relay 952 is permitted to deenergize to ring the subscriber at substation A.

Upon the removal of the receiver an energizing circuit is completed over the heavy conductors for the double wound relay 860 at the toll second selector W' in an obvious manner. By the operation of relay 860 the following functions are performed: At armature 853 ground is connected to the control circuit extending to connector H' to provide against the deenergization of relay 826; at armature 850 the conductor 802 is disconnected from relay 826 and is connected instead to the winding of relay 827 (with results which will be presently explained); and at armatures 851 and 852 the A. C. relay 880 is disconnected from the line, and the heavy incoming line conductors and the heavy out-going line conductors are joined together. At the operator's cord circuit the supervisory lamp L' is extinguished by the deenergization of relay 25, which relay is marginally adjusted and is caused to retract its armature when the high resistance relay 827 is substituted for the low resistance relay 826 in its circuit.

The complete talking connection between substation A in the No. 1 exchange and substation A³ in the No. 3 exchange has now been established and the subscribers may converse as desired. Current for the transmitter at substation A is supplied through the windings of the double wound relay 860 at the toll second selector W'; while current for the transmitter at substation A³ is supplied through the windings of the double wound relay 660 at the toll second selector W³. The voice currents follow the heavy conductors. Attention is called to the fact that the talking circuit is of high efficiency. Except for the repeating coils R and R² the connection is metallic throughout, and the bridges across the talking circuit have been reduced to the lowest possible number.

When the conversation is finished both subscribers will hang up their receivers. The replacement of the receiver at substation A causes the bridged relay 860 at the toll second selector W' to deenergize, whereby the low resistance line relay 826 is once more included in the circuit of the supervisory relay 25 at the operator's cord circuit, the high resistance relay 827 being cut out. By the consequent energization of relay 25 the lamp L' is lighted up to inform the op-

erator that the subscribers are through talking.

Disconnection is now effected by the removal of both plugs from the jacks. When the plug is removed from jack J, the circuit 70 of relay 826 of the toll second selector W' is broken. Relay 826, upon deenergizing, breaks the circuit of relay 827 and also opens the control circuit extending to the line relay 926 of the connector H'. By the de- 75 energization of relay 827 the circuit of the release magnet 829 is closed and the selector W' is restored to normal in the usual manner, the release magnet circuit being opened when the shaft reaches its normal position. 80 As a further result of the deenergization of the relay 827, ground G³⁸ is removed from the holding circuit of the switching relay 808 of the selector V', where by the deenergization of the said relay 808, a circuit is 85 closed for the release magnet 814. The release magnet 814 operates to restore the selector V' to normal position, its circuit being opened by the return of the shaft in the usual manner. At the connector H' the relay 926 is deenergized to open the circuit of relay 927, which relay, upon deenergizing in turn, closes the circuit of the release magnet 929, whereby the connector H' is restored to normal position also. All the 95 equipment used in completing connection to substation A is therefore released and ready for another call.

From the foregoing the operation of restoring the remainder of the apparatus will 100 be readily understood without going into further details, it being understood that the various control circuits extending from one switch to the next are successively opened in response to the removal of the plug 105 from jack J' in the same order in which they were established. Briefly, the toll selector repeater M', the toll rotary connector N, the toll selector repeater M³, the toll second selector W³, and the connector H³ are 110 restored to normal, respectively, through the medium of their release magnets 229, 313, 529, 629, and 757, all upon the deenergization 115 of their respective controlling relays, and in the usual and well understood manner.

Having described the process of establishing and releasing the complete long distance connection shown in the drawings, I will now explain a number of details which it 120 was not convenient to touch upon before. We will take up first the operation of a connector such as the connector H' when a busy line is called by the operator. Referring to Fig. 1, it is understood that whenever the 125 line of substation A is busy the test contact 22 will have ground potential upon it. In the operation of connector H' therefore, when the relay 928 deenergizes after the last series of impulses, if the line of substation 130

A is busy the following circuit will be established: ground on test contact 22, private wiper 946, side switch wiper 971 (in second position), contact springs of test relay 954 and the winding of the said relay, contact springs of relay 928, and the winding of the private magnet 956 to battery B⁴². By the closure of the above circuit, the private magnet is maintained energized to retain the side switch wipers in second position. The test relay 954 is energized in series with the private magnet and upon attracting its armature 992 locks itself over the following path: ground on test contact 22, private wiper 946, working contact of armature 963 and the said armature, and armature 992 and its working contact to the winding of the said test relay, whence the circuit continues as previously explained. The locking circuit is in reality no locking circuit at all, for the normal locking operation performed by the armature 992 of the test relay is nullified by the switching of the circuit at armature 963 of relay 951. Thus the continued energization of relay 954 depends on the continued busy condition of the line of substation A. As a further result of its energization, the test relay 954 opens the rotary magnet circuit at its armature 991, and at its armature 993 connects the low resistance secondary of the transformer of the busy signaling machine Q to the lower incoming heavy line conductor by way of resistance r⁵. By the latter operation, an energizing circuit is completed for the relay 860 of the toll second selector W' as follows: ground at G⁴², lower winding of relay 860, working contact of armature 874 and the said armature, wiper 848 and the bank contact engaged thereby, working contact of armature 965 and the said armature, resistance r⁵, working contacts of armature 993, and the secondary of the busy machine transformer to battery B⁴³. The transformer secondary is of such low resistance that the alternative path to battery by way of armature 993, lower winding of back bridge relay 918, and upper winding of relay 955, is practically short circuited. Upon energizing, relay 860 connects the heavy incoming and outgoing line conductors, whereupon the operator is enabled to hear the busy signal, and also substitutes high resistance relay 827 for the low resistance relay 826 in the control circuit which includes the supervisory relay 25 at the operator's cord circuit. Upon perceiving the busy signal the operator need not release the connection but instead will operate the cut-off key K⁸ to prevent the subscriber at the other end (if one is connected) from hearing the busy signal; and will restore her keys K' and K⁴, thus leaving the connection to the busy called line under control of the supervisory lamp L'. As soon as the line

becomes idle the test relay 954 and the private magnet deenergize, whereupon the side switch wipers advance to their third position and the wiper switching relay 953 is energized to complete the connection to the line wipers as usual. By the deenergization of the test relay the busy signaling machine is disconnected from the lower incoming heavy line conductor and consequently the relay 860 of the toll second selector W' is deenergized. As a result the control circuit including the supervisory relay 25 is again completed by way of the line relay 826, and the relay 25 is accordingly operated to light the lamp L', whereby the operator is informed that the called line has become idle. I will now describe a feature of the cord circuit which has been previously mentioned briefly and which is concerned with the altering of the resistance of the ring-down relay 26 under control of the supervisory relay 25. We will assume that in response to a call from the No. 2 exchange, the operator at the No. 1 exchange has established the connection shown in Figs. 1, 2 and 3 of the drawings. Now when the subscriber at substation A answers, the supervisory relay 25 is deenergized and both windings of the ring-down relay 26 are connected in series in bridge of the talking strands of the cord circuit. The winding 31 is of extremely high resistance and impedance so as not to appreciably reduce the talking efficiency. When the conversation is finished and the subscriber at substation A hangs up his receiver, relay 25 is energized again to light the lamp L' and to cut out the high resistance winding 31 of relay 26. Assume now that the operator at the No. 1 exchange is busy and does not at once pull down the connection. The No. 2 exchange operator, however, disconnects at her end of the toll line immediately and, desiring to obtain another connection, rings the No. 1 exchange operator over the same toll line. The bridged relay 26 is therefore operated by means of its winding 30 to open the short circuit of winding 29 of locking supervisory relay 27. Both windings of relay 27 now carry current and the said relay is operated to remove the short circuit from its winding 29 independent of relay 26 and to light the lamp L². Since the plug is still in jack J of the service trunk, if the effective resistance of relay 26 was not very low, part of the ringing current would traverse the heavy line conductors to the A. C. relay 880 of the toll second selector W' and would actuate the said relay to again signal the subscriber at substation A. This objectionable result is entirely prevented by the double wound arrangement of relay 26, the resistances of the windings concerned being approximately as follows: winding 30 of relay 26, 200 ohms; winding 31 of relay 26, 2000 ohms; 130

and winding of A. C. relay 880, 2000 ohms. These resistances give good results in practice although of course the exact values need not be adhered to.

5 Brief consideration will now be given to the operation of a connector switch such as the connector H' or H³ when in use for completing local connections. Referring to Fig. 11, we will assume that the connector H³ has 10 been seized by a local second selector F³ (Fig. 12) which may be similar to the second selector shown in the previously mentioned patent to Newforth, Reissue No. 13,901. When the local selector has operated to establish connection with the trunk 15 conductors 708, 701 and 709, the line relay 726 of the connector H³ is energized over the two line conductors 708 and 709 in series as in the system illustrated in the above 20 mentioned patent. Relay 727 is then operated to ground conductor 701 to provide a holding circuit for the selector switch in the usual manner. The test contact 700 and its multiples are also grounded by way of 25 the windings of low resistance relays 751 and 752 and conductor 703 whereby the connector H³ is made busy to the toll second selectors. Now since no current flows over the conductor 703, except slight 30 momentary impulses due to toll second selectors passing over the busy test contact 700 and its multiples, the relays 751 and 752 remain deenergized.

Under control of the calling device at the 35 calling substation the connector is now operated to complete the connection to the wanted line in substantially the same manner as has already been described. When the side switch wipers have advanced to 40 their third positions, current is supplied to the winding of the wiper switching relay 753 and the cut-off winding of line switch C' from ground G³² instead of from ground G³¹, as would be the case if the connector H³ were being used to complete a toll 45 connection. As soon as relay 753 energizes the called subscriber is signaled over the following circuit: ground at G⁴⁶, generator Gen², 50 working contact and armature of relay 799, lamp L¹⁰, resting contact of armature 762 and the said armature, resting contact of armature 797 and the said armature, armature 768 and its working contact, wiper 748, bank contact 22', to and through substation 55 A³, bank contact 21', wiper 745, working contact of armature 767 and the said armature, armature 795 and its resting contact, armature 761 and its resting contact, and the lower winding of relay 755 and battery 60 B⁴⁴ to ground G⁴⁴. By the operation of the apparatus IR² the generator Gen² is intermittently cut out of circuit and the battery B⁴⁵ substituted therefor. Relay 755 is so 65 adjusted that it will operate on the generator current when the receiver at the called

substation is off the hook, or on the current from batteries B⁴⁴ and B⁴⁵ in series under the same condition; but it will not be operated by generator current when the receiver at a called substation is on the hook. 70

When the called subscriber responds, therefore, relay 755 is energized at once, irrespective of the position of interrupter equipment IR², and locks itself over the following path: ground at G⁴⁶, off normal contact 758, working contact of armature 796 and the said armature, and the upper winding of relay 755 to battery B⁴⁴. By attracting its armatures 795 and 797, relay 755 disconnects the intermittent ringing apparatus 75 and connects the talking conductors 708' and 709', respectively, to the line wipers 745 and 748, whereupon a talking connection from the calling local subscriber to the subscriber at substation A³ will have been 80 established. Current for the transmitter at substation A³ is under these circumstances supplied through the windings of the back bridge relay 718, which relay is energized to reverse the incoming line conductors 708 90 and 709 in order to operate a meter or other apparatus in the well understood manner.

The operation of the connector H³ (or connector H') when calling a busy line is substantially the same whether such connector is in use by a local subscriber or by a toll operator, with one exception however. Referring to Fig. 11, when the test relay 754 is energized by a ground potential on a busy test contact, such as test contact 22', 100 a locking circuit is established as follows: ground at G⁴⁶, off normal contact 758, resting contact of armature 763 and the said armature, armature 798 and its working contact, winding of relay 754, contact springs 105 of relay 728, and the winding of the private magnet 756 to battery B⁴¹. Thus it will be seen that the test relay and the private magnet will be locked up as long as the connector remains in operated position. 110

Referring now to Fig. 5, it has been mentioned before that the condenser 255 is short circuited upon the operation of relay 226. The utility of this arrangement will now be explained. Owing to their limited capacity, 115 or for other reasons which we need not discuss, it may be that one or more exchanges in a system will not be equipped with the special toll service trunks, all connections whether toll or local being completed with 120 the same kind of switches. Selector repeaters such as the selector repeater M' may still be used to complete automatic toll connections however, in the following manner: In a 1000 line system, the trunk lines 125 extending to the connector switches, which by the way may be of the type shown in the previously mentioned patent to Newforth, Reissue No. 13,901, are multiplied in the banks of the toll selector repeaters, so that 130

these selector repeaters have access to the connectors in common with the first selector switches. With this arrangement the wipers 245 and 248 of the selector repeater M' would engage the two line conductors of a selected trunk, respectively, while the wiper 247 would engage the release conductor of the trunk. In Fig. 11, similar conductors are indicated by reference characters 708, 709, 10 and 701. The wiper 246 of the selector repeater M' would perform no function whatever. Now when a connector switch is seized by a selector repeater (selector repeater M', for example), the line relay of the connector 15 is energized over the two line conductors in series and a closed loop in the selector repeater which is traceable in selector repeater M' as follows: wiper 245, working contact of armature 273 and the said armature, armature 235 and its resting contact, upper right hand winding of repeating coil R', working contact of armature 254 and the said armature, lower right hand winding of repeating coil R', resting contact of armature 236 and the said armature, and armature 274 and its working contact to wiper 248. It will be clear now without further explanation that when relay 226 is deenergized intermittently in response to interruptions of its circuit, similar interruptions will be produced in the circuit of the line relay of the connector switch, whereby the connector may be operated to connect with a called line.

Attention is now called to the selector repeater M^a (Fig. 9) for the purpose of explaining an alternative method of connecting the line conductors extending to the tip and ring springs of jack J^a. In the selector repeater M^a, it will be observed that these 35 conductors are terminated in the resting contacts of armatures 535 and 536, respectively; while in selector repeater M' (Fig. 5), the corresponding conductors are terminated, respectively, in armatures 235 and 236 direct. 40 The method of connection adopted depends on whether or not the operator is to be allowed supervision on automatic through connections or not. Usually, in a large switching exchange, it will be found advisable to permit the operators to plug into busy lines in order to observe the progress of calls, or for general purposes of supervision over the smaller exchange operators. Thus in the selector repeater M' the jack J^a 45 is left in bridge of the heavy line conductors after the relay 224 has operated. But in a smaller exchange it may be desired to exclude the operators entirely from any interference with lines which are busy on 50 through connections. This is accomplished by wiring the selector repeaters as shown in Fig. 9, in which circuit, when the relay 524 is operated on a through connection, the conductors extending to the jack J^a cut off. 55 Referring to the drawing, in the apparatus

known as composite ringing apparatus which I have indicated by the reference characters U and U' in Fig. 8, means is provided for receiving the usual ringing current at one end of the toll line such as Z, and for translating said ringing current into a high frequency alternating current which is delivered out over the trunk line Z and which is received by a similar reversed apparatus U' at the opposite end of trunk Z, which apparatus U' again translates the high frequency alternating current back into normal ringing current which is sent out to the called operator or subscriber. It will be understood that the apparatus U' is exactly similar to the apparatus U except that the circuits will be reversed. When ringing current is received over the trunk line conductors 2' and 3' in series this current passes through the alternating current relay 4' and 60 sensitive alternating current relay 5' in multiple. Only the relay 4' operates at this time to open the circuit of the sensitive alternating current relay 5' and to connect the high frequency generator 6' to the trunk line Z. 65 The closure of this circuit causes high frequency alternating current to be projected over the two conductors of the trunk line Z. This high frequency alternating current has no effect upon the apparatus associated with 70 the trunk line but is received by the apparatus U' at the opposite end thereof. The sensitive alternating current relay 10' operates by this high frequency current while the relay 9' is not operated. The relay 10' 75 operates to connect the low frequency generator 11' to the outgoing conductors leading to the called operator or subscriber. In addition to the patent to Fell, previously mentioned, reference is had to the patent to Field, No. 619,157, as disclosing similar apparatus. It 80 may be mentioned, however, that the lower grounded circuit, shown in Fig. 8 as being used for telegraphic purposes, may be used as a switch control circuit for a second toll 85 line. In such case, it would be unnecessary to equip the second toll line for composite 90 operation, thus adding to its transmission qualities.

Having described my invention, what I 95 consider to be new and desire to have protected by Letters Patent will be pointed out in the appended claims.

What I claim as my invention is:—

1. In an automatic telephone system, means 100 for extending connection from a toll line to a local subscriber, said means comprising first and second selector switches and connector switches, means whereby operators may call local subscribers, said second means 105 comprising a separate plurality of first selectors individual to the operators and the said second selectors and connectors, and means for interconnecting local subscribers' 110 lines, said last means comprising additional 115

plurality of first and second selector switches accessible only to local subscribers and said connectors.

2. In a telephone system, two trunk lines 5 of different character both terminating in the same connector switch, said switch having different operating functions characteristic of the different trunk lines, a line relay for controlling the operation of said switch, 10 means for energizing said relay over the two conductors of one of said trunk lines when a connection is established thereover, and means for energizing said relay over a conductor separate from the conductor of the 15 other trunk line when connection is established over said other trunk line.

3. In a telephone system, two trunk lines 20 of different character both terminating in the same connector switch, said switch having two separate ringing circuits and two separate talking circuits characteristic of the different trunk lines, a test conductor associated with each trunk line, and a relay in series with one of said test conductors and 25 controllable thereover, said relay when operated effective to interchange said ringing and talking circuits.

4. In a telephone system, a plurality of connector switches for completing connections to called lines, said switches being accessible in common to calling subscribers and to operators, means for preventing a connector switch from completing connection with a busy called line while retaining such 35 switch in operated position, means for then completing the connection as soon as the called line becomes idle, and discriminating means in each connector dependent on whether or not such connector is in use by 40 an operator for rendering said last means effective.

5. In a telephone system, a connector switch for completing connection to a called line, trunk lines of two kinds and associated automatic switches for connecting the 45 several trunk lines with said connector switch separately, means for operating said connector switch over a connected trunk line, means for preventing said connector 50 switch from completing connection to a busy called line, means for automatically completing the connection when the called line becomes idle, a relay for controlling said last means, and a circuit for said relay completed only over a trunk line of a particular 55 kind.

6. In a telephone system, a connector switch for completing connections to called subscribers' lines, said connector accessible 60 to calling subscribers and to operators in common, means in said connector for performing automatic or operator controlled signaling operations on a called line and discriminating means dependent on whether 65 said connector is being used by a calling

subscriber or by an operator for determining the character of the signaling operation.

7. In a telephone system, a connector switch for completing connections to called subscribers' lines, said connectors accessible 70 in common to calling subscribers and to operators, means in said connector for automatically signaling a called subscriber, means in said connector controllable by an operator for signaling a called subscriber 75 and discriminating means dependent on whether said connector is being used by a calling subscriber or by an operator for determining the character of the ringing operation. 80

8. In a telephone system, a connector switch for completing connections to called subscribers' lines, a local and a toll selector which have access to said connector over separate trunk lines, and means for supplying 85 a called line with talking battery either from a bridge in said connector or from a bridge in said toll selector.

9. In a telephone system, a connector switch for completing connections to called 90 subscribers' lines, a local and a toll selector which have access to said connector over separate trunk lines, and means for supplying a called line with talking battery either from a bridge in said connector or from a 95 bridge in said toll selector and means in said connector for preventing the closure of said first named bridge when said connector is seized by said toll selector.

10. In a telephone system, a subscriber's 100 trunk line and an operator's trunk line, a plurality of serially related switching devices common to said trunk lines for extending either to a called line, a relay in one of said devices for supplying talking current 105 to a called line only when said devices are in use by the operator, and a relay in another of said devices for supplying talking current to the called line only when said devices are in use by a subscriber. 110

11. In a telephone system, a connector switch provided with movable terminals co-operating with the fixed terminals of called lines, separate pairs of talking conductors terminating in said switch, and relays in 115 said switch for connecting said pairs separately with said movable terminals.

12. In a telephone system, an automatic switch, separate pairs of talking conductors extending from different points and terminating in said switch, means for controlling the operation of said switch over the conductors of one of said pairs in series, a third conductor associated with the other of said pairs and joined at the said switch 120 to a conductor of said first pair, and means for controlling the operation of said switch over said third conductor to the exclusion of the associated talking conductors. 125

13. In a telephone system, two trunk 130

lines terminating in the same automatic switch, a double wound line relay for said switch, means for completing a control circuit over one of said trunk lines including 5 both windings of said relay in series, and means for completing a control circuit for said switch over the other of said trunk lines including only one winding of said relay.

14. In a telephone system, an automatic 10 switch, a trunk line terminating in a second automatic switch, means for operating said first switch to connect with said trunk line, means for operating said second switch by impulses of current transmitted over a third 15 conductor exclusive of the talking conductors of said trunk line and a circuit controlled by a relay in said first switch for maintaining said second switch in operated position, said circuit including a fourth 20 conductor of said trunk line exclusive of the talking conductors thereof.

15. In a telephone system, a calling subscriber's line and a called subscriber's line, connecting means for establishing a continuous 25 metallic talking circuit from the calling to the called line, said means comprising in serial relation an operator's cord circuit, a plurality of selector switches, and a final connector switch.

30 16. In a telephone system, a calling subscriber's line and a called subscriber's line, connecting means for establishing a continuous metallic talking circuit from the calling to the called line, said means comprising 35 an operator's cord circuit, a plurality of selector switches, and a final connector switch.

17. In a telephone system, a calling and a called line, connecting means for establishing a continuous metallic talking circuit 40 between said lines, said means comprising in serial relation an operator's cord circuit, a plurality of selector switches, and a final connector switch, a third conductor independent of the talking circuit associated 45 with each switch, and means for operating each switch over its associated third conductor.

18. In a telephone system, a calling and a called line, connecting means for establishing 50 a continuous metallic talking circuit between said lines, said means comprising in serial relation an operator's cord circuit, a plurality of selector switches, a final connector switch, a third conductor independent of the talking circuit and including the 55 third strand of said cord circuit, and means for controlling the operation of said switches over said conductor.

19. In a telephone system, means for extending 60 a connection to a called line, said means comprising a cord circuit, selector switches and a connector switch, a temporarily established continuous metallic talking circuit including the tip and ring strands 65 of said cord circuit, selectively movable con-

tacts in a plurality of said selectors, and selectively movable contacts in said connector, and a relay in bridge of the talking conductors at one of said selectors for controlling the continuity of said talking circuit. 70

20. In a telephone system, means for extending a connection to a called line, said means comprising a cord circuit, selector switches and a connector switch, a temporarily established continuous metallic talking circuit including the tip and ring strands of said cord circuit, selectively movable contacts in a plurality of said selectors, and selectively movable contacts in said connector, a relay in bridge of the talking conductors at one of said selectors for controlling the continuity of said talking circuit, and a battery in series with said relay for supplying talking current to the connected 85 called line. 75

21. In a telephone system, means for extending a connection to a called line, said means comprising a cord circuit, selector switches and a connector switch, a temporarily established continuous metallic talking circuit including the tip and ring strands of said cord circuit, selectively movable contacts in a plurality of said selectors, and selectively movable contacts in said connector, a relay in bridge of the talking conductors at one of said selectors for controlling the continuity of said talking circuit, and means controlled independent of the 90 called line for releasing the connection. 95

22. In a telephone system, a temporarily established connection including a selector switch, a connector switch, and a called line, a ringing relay in the connector for signaling the called line, a relay in bridge of the talking conductors at the selector switch responsive to alternating current, and a circuit independent of the talking conductors extending between the said selector and connector over which said second relay controls 105 the operation of said first relay. 110

23. In a telephone system, a selector switch, a connector switch, and a called subscriber's line, a continuous metallic talking circuit in two sections, the first of said sections terminating at contacts of a relay in said selector, and the second of said sections terminating also at contacts of said relay and including selectively movable contacts of said selector, selectively movable contacts of said connector, and the said subscriber's line, a bridge across the talking conductors of said second section including a battery and the winding of said relay, a second relay responsive to alternating current normally bridged across the talking conductors of said first section, said second bridge under the control of said first relay, signaling means in said connector controlled by said second relay over a circuit inde- 115 120 125 130

pendent of the talking conductors, and means controlled by the called subscriber for closing the two limbs of his line to operate said first relay whereby the said second relay bridge is disconnected and the said two sections are joined together.

24. In a telephone system, a trunk line terminating in a selector switch, a repeating coil in said trunk line, other trunk lines of two kinds accessible to said selector switch, means for operating said switch to connect said first trunk line with another trunk line of either kind, and means in said selector switch able to discriminate between the different kinds of trunk lines when such connections are established and operative to cut out said repeating coil if a particular kind of trunk line is connected with.

25. In a telephone system, two toll lines each terminating in a central exchange, line extensions for said toll lines in said exchange, inductive devices comprising repeating coils for connecting each toll line with its respective line extension, automatic means for connecting said toll lines via their respective line extensions, and automatic means for eliminating one of said repeating coils from the connection.

26. In a telephone system, two toll lines terminating in a central exchange, line extensions for said lines at said exchange, inductive devices comprising repeating coils for connecting each toll line with its respective line extension, a local trunk line in said exchange, a selector switch associated with one of said line extensions, means including said switch for connecting the associated line extension either with the said local trunk line or with the other line extension, and automatic means operated in the latter case only for eliminating one of said repeating coils.

27. In a telephone system, a trunk line comprising two inductively connected sections of a metallic talking circuit, an automatic switch in which one of said sections terminates, other lines of two kinds accessible to said switch, means for operating said switch to connect said trunk line with a line of either kind, a relay for directly connecting the talking conductors of one of said sections, respectively, with the talking conductors of the other of said sections, and means for operating said relay only when a line of a particular kind is connected with.

28. In a telephone system, a trunk line terminating at one end in movable contacts in a first switch and fixed contacts in a second switch, an operator's jack and call signal in bridge of said line at the same end, means for seizing said trunk line at the other end, means responsive to such seizure for placing a busy potential upon one of the fixed contacts in said second switch, means for operating said first switch over said

trunk line, and means actuated responsive to the movement of said first switch for disconnecting said call signal.

29. In a telephone system, a trunk line terminating in an automatic switch, a branch of said trunk line extending to a jack at an operator's position, other lines of two kinds accessible to said switch, means for operating said switch to connect said trunk line with another line of either kind, and means for disconnecting said branch only when a particular kind of line is connected with.

30. In a telephone system, a trunk line terminating in an automatic switch, a branch of said trunk line extending to a jack at an operator's position, other lines of two kinds accessible to said switch, means for operating said switch to connect said trunk line with another line of either kind, a relay for disconnecting said branch, and means effective only when a particular kind of line is connected with for operating said relay.

31. In a telephone system, a group of trunk lines having line terminals arranged in a row, another set of line terminals in the row from which a trunk extends to an operator's position, an automatic switch, means for automatically rotating the wipers of said switch over the terminals of said trunk lines when the same are busy, a relay in said switch connected in bridge of said line terminals successively by the advance of said wipers, a battery in bridge of the trunk extending to the operator's position for energizing said relay, and means controlled by said relay for stopping the further movement of said wipers.

32. In a telephone system, a temporarily established connection between a calling and a called line including an operator's cord circuit, a supervisory relay bridged directly across the talking conductors of said cord circuit, and means controlled by the subscriber on a connected line for including a resistance in said bridge.

33. In a telephone system, an operator's cord circuit for connecting lines in conversation and comprising answering and calling plugs, metallic talking conductors extending without interruption between said plugs, an inductive bridge across said conductors, and means controlled by the subscriber on a connected line for altering the resistance of said bridge.

34. In a telephone system, an operator's cord circuit for connecting lines in conversation and comprising answering and calling plugs, metallic talking conductors extending without interruption between said plugs, a double wound supervisory relay in bridge of said conductors, and means controlled by the subscriber on a connected line for cutting one of said windings in or out of the bridge.

35. In a telephone system, an operator's cord circuit comprising talking conductors and a third conductor at each end thereof, an operator's telephone set and a listening key for connecting said set in bridge of said talking conductors, a calling device, and a combined calling device and cut-off key at each end of said cord circuit, each key when actuated operating to disconnect the talking conductors at one end from said telephone set and to connect said calling device in circuit with the third conductor at the other end.

36. In a telephone system, an operator's cord circuit comprising a pair of talking strands, a supervisory bridge of said strands including only a magnet, a supervisory relay associated with one end of said cord circuit and means for energizing said relay to include a resistance in said bridge.

37. In a telephone system, an operator's cord circuit comprising a pair of talking conductors, a signal, a relay for controlling said signal, said relay having two windings serially connected in bridge of said talking conductors, an inductive device in said bridge, a second relay and a signal controlled thereby, and means controlled by said second relay for removing one of the windings of said first relay and said inductive device from said bridge.

38. In a telephone system, a temporarily established connection between a calling and a called line including an operator's cord circuit and a selector switch, a controlling circuit for said switch including a low resistance controlling relay therein, the third strand of said cord circuit and a second relay in said cord circuit, a signal under control of said second relay, a high resistance release control relay in said selector, and means controlled by the response of the called subscriber for substituting said release relay for said control relay in said circuit whereby the resistance of said circuit is increased to cause the deenergization of said second relay.

39. In a telephone system, a temporarily established connection between a calling and a called line including an operator's cord circuit and an automatic switch for establishing a talking circuit, a pair of control relays in said switch of different resistances, a circuit separate from said talking circuit including one of said relays and a supervisory relay in said cord circuit, and means controlled by the called subscriber for substituting the other relay of said pair in said circuit to effect the control of said supervisory relay.

40. In a telephone system, a trunk line comprising first and second sections, inductive windings in bridge of each section, an automatic switch in which the second section terminates, a control circuit for said

switch including the talking conductors of the first section in parallel and the inductive windings in bridge thereof, means for producing current changes in said circuit to cause the operation of said switch, and automatic means for disconnecting the inductive windings in bridge of said second section and for connecting the conductors thereof directly to the conductors of said first section.

75

41. In a telephone system, a trunk line comprising first and second sections, inductive windings in bridge of each section, an automatic switch in which the second section terminates, a control circuit for said switch including the talking conductors of the first section in parallel and the inductive windings in bridge thereof, means for producing current changes in said circuit to cause the operation of said switch, automatic means for disconnecting the inductive windings in bridge of said second section and for connecting the conductors thereof directly to the conductors of said first section, and impedance coils, said last means effective also to connect said coils in series with the inductive windings in bridge of said first section.

90

42. In a telephone system, a trunk line comprising first and second sections, inductive windings in bridge of each section, an automatic switch in which the second section terminates, a control circuit for said switch including the talking conductors of the first section in parallel and the inductive windings in bridge thereof, means for producing current changes in said circuit to cause the operation of said switch, means for disconnecting the inductive windings in bridge of said second section and for connecting the conductors thereof directly to the conductors of said first section, other lines of two kinds with which said switch is adapted to establish connection, and a relay operated only when a particular kind of line is connected with for controlling the operation of said last means.

95

43. In a telephone system, subscribers' lines, a trunk line common to said subscribers' lines connecting two points and comprising two metallic conductors, separate ground return circuits each including one of said conductors and a source of current, and means including an automatic switch controllable exclusively over one of said circuits for establishing a talking connection over the two conductors of said line.

115

44. In a telephone system, two groups of subscribers' lines, a two conductor trunk line extending between said groups, means for establishing talking connections over the two conductors of said trunk line in either direction, automatic switches at each end of said trunk line for use in establishing the said connections, and means at each end for

125

130

operating the switches at the other end over one of said conductors independent of the other conductor.

45. In a telephone system, two groups of 5 subscribers' lines, a two conductor trunk line extending between said groups, manual equipment for establishing talking connections over the two conductors of said trunk line, means including automatic switches at 10 each end of said trunk line for establishing talking connections thereover in either direction, and means at each end for controlling the operation of the switches at the other end over one of said conductors independent of the other conductor, a telegraph circuit including the last conductor and independent of the first, and means for preventing interference between the telegraph, switch control, and talking circuits.
- 15 46. In a telephone system, a toll line connecting two exchanges, condensers in series

with the line conductors at each exchange, a bridge across the conductors of said toll line at the exchange side of the condensers at each end, each bridge comprising a condenser, serially related inductive windings, and another condenser, a second bridge across the conductors of said toll line on the line side of said first condensers at each end, each second bridge including an inductive winding, a pair of condensers and another inductive winding, an automatic switch at one exchange, and a control circuit for said switch including only one of the said inductive windings of the said second bridge at each exchange and only one of the conductors of said toll line.

Signed by me at Chicago, Cook county, State of Illinois, this 3rd day of October, 1916.

JOHN WICKS.
